UNITED STATES PATENT OFFICE.

HYMAN MUSKIN, OF BALTIMORE, MARYLAND.

SHOE.

1,389,455.

Specification of Letters Patent. Patented Aug. 30, 1921.

Application filed February 5, 1920. Serial No. 356,375.

To all whom it may concern:

Be it known that I, HYMAN MUSKIN, a citizen of the United States of America, residing at Baltimore, in the State of Maryland, have 5 invented new and useful Improvements in Shoes, of which the following is a specification.

The object of the invention is to provide a shoe and method of constructing the same 10 whereby the stitching which serves to secure the vamp or upper to the sole is reinforced and is relieved of a portion of the strain incident to the use of the shoe and tending to break the stitches and thus release the inner turned marginal edge of the vamp, and also to provide reinforcing means in this connection whereby in the event of loosening or breaking of the stitches by which the vamp is connected with the sole, the possibility of dis- 15 placement outwardly are the liberation of the edge of the vamp, and the protrusion thereof beyond its proper relation with the sole is minimized or eliminated; furthermore to provide a construction which while 20 adapted to shoes of the pliable or soft-soled type, such as house shoes, slippers, etc., is also suitable for hard-sole shoes, to the end that the reinforcement of the stitching by which the vamp is secured to the sole may be 25 effected without exposure of the line of stitching or the arrangement of the same so that it is visible at the exterior of the completed shoe, but on the other hand under such 30 conditions as to be located inside of the line of rise of the vamp from the outer sole; furthermore, to provide a construction of shoe and a method of producing the same whereby, with special reference to those of the hard-soled type, the necessity for lasting 35 40 is obviated, and whereby the completed product is finished inside to afford a perfectly smooth and even bearing surface for the foot of the wearer, to the end that it is especially adapted, as primarily designed, 45 for use as a "first-step" shoe for infants making their first attempt to walk, and in which connection a shoe having a relatively stiff sole as a means of fortifying the efforts of the wearer in maintaining an equilibrium is 50 essential; and furthermore to so arrange the reinforcing means with relation to the marginal edge of the vamp and the line of stitching whereby said marginal edge is secured to the outer sole, that an inner sole, 55 either attached or separate, that is either secured or removably fitted may be employed,

and in this connection to provide means whereby the securing of the insole, when so desired, may be accomplished by means common to the construction contemplating 60 the independent application of the insole and under such conditions as to still further reinforce the relations between the vamp and the sole and supplement the primary reinforcing element. 65

With these objects in view the invention consists in a construction, combination and relation of parts and a method of assembling the same, of which a preferred embodiment is illustrated in the accompanying drawing, 70 it being understood that changes in forms, proportions and details may be resorted to within the scope of the claims without departing from the principles involved. 75

In the drawing:

Figure 1 is a transverse sectional view of a shoe embodying the invention, the insole being arranged and secured to perform the function of a supplemental reinforcing medium. 80

Fig. 2 is an enlarged detail section similar to Fig. 1 with the elements separated to show their specific relations. 85

Fig. 3 is a sectional view of a shoe constructed in accordance with the invention wherein the supplemental reinforcing agency of the insole is omitted. 90

Fig. 4 is a sectional view of a construction similar to that indicated in Fig. 1 wherein the seam by which the marginal edge of the 95 vamp is secured to the lining or stay is arranged exteriorly instead of interiorly, to avoid the turning of the vamp after its attachment to the lining.

In the construction of the improved shoe 95 the inturned edge 10 of the vamp shown at 11 is marginally secured by a line of stitching indicated at 12 with a transverse lining or stay 13 of fabric, thin leather, canvas or equivalent material preferably having a substantial tensile strength not subject to material stretch, and arranged in contact with the exterior surface of said lining or stay and in overlapping relation with the in-turned edge of the vamp is the main or outer sole 14 which is connected with said in-turned edge of the vamp by a line of stitching 15 disposed in a concealed relation with the upper of the shoe is in a plane inside of the rise of the vamp from the sole as indicated at 16. When the seam connecting the marginal edge of the vamp with the lining 105 110

or stay 13 is arranged to project inwardly or upwardly as shown in Figs. 1 and 2, it should be formed obviously with the upper in a reversed position, after which the upper 5 should be turned to permit of the stitching of the outsole to the inturned edge of the vamp on a plane between said line of stitching 12 and the rise of the vamp from the sole.

10 It will be noted that the effect of the lining or stay which is in a taut relation to the vamp is to reinforce the line of stitching by which the main or outsole is attached to the inturned edge of the vamp by relieving 15 said line of stitching of a large percentage of the outward strain applied to the vamp and tending to stretch or break the stitches, and in the event of such stretching or breaking the marginal edge of the vamp is still 20 held by the lining or stay and is prevented from turning outward or bulging or protruding and thus rendering the article not only unsightly but uncomfortable.

As a means of still further reinforcing 25 the connection between the outsole and the vamp, the insole 17, as indicated in Figs. 1 and 2 may be arranged upon the inner surface of the lining or stay 13 in marginal overlapping relation with the inturned edge 30 of the vamp and may be engaged at its edge by the same line of stitching indicated at 15 which serves to secure the outsole of the vamp edge, so that the seam or line of stitching which serves to connect the marginal 35 edge of the vamp with the lining or stay is disposed between the planes of the outsole and insole and while being protected from wear or the effect of friction incident to the use of the shoe is maintained in flat relation with the adjacent surfaces of said insole 40 and outsole so as to afford no discomfort to the wearer.

Or as indicated in Fig. 4 the joint between the marginal edge of the vamp and the lining or stay may extend downwardly or outwardly to lie in contact with the inner surface of the outsole, so as to be rendered unobjectionable whether an insole is employed

or not, it being possible under some conditions that a relatively thin sock lining 18 50 may be preferred to an insole.

In the construction illustrated in Fig. 3 the insole 19 while disposed in contact with the inner surface of the lining or stay 13^a and preferably extends laterally into overlapping relation with the inturned edge 10^a of the vamp, is unengaged by the line of stitching 15^a which serves to secure the in-turned edge of the vamp to the main or outsole 14^a, but as in the construction shown in 60 Figs. 1 and 2 said vamp securing stitches 15^a engage the inturned edge thereof between the line of the seam 12^a connecting the marginal edge of the vamp with the lining or stay and the rise 16^a of the vamp from the 65 main or outsole.

What is claimed is:

1. The method of constructing a shoe which consists in stitching the marginal edge of the vamp to a flexible lining or stay, 70 turning the vamp, applying a sole to the exterior surface of the lining or stay in overlapping marginal relation with the adjacent portion of the vamp and stitching the marginal portion of the sole to the vamp outside of the seam between the latter and said lining or stay and inside of the rise of the vamp from the sole.

2. The method of constructing a shoe 80 which consists in stitching the marginal edge of the vamp to a flexible lining or stay, turning the vamp, applying an outer sole to the exterior surface of the lining or stay and an inner sole to the interior surface of the lining or stay, both outsole and insole being 85 in overlapping marginal relation with the portion of the vamp adjacent to the edges of said lining or stay, and stitching the marginal portions of said outsole and insole to the vamp outside of the seam between the 90 latter and said lining or stay and inside of the rise of the vamp from the sole.

In testimony whereof I affix my signature.

HYMAN MUSKIN.
